UNITED STATES PATENT OFFICE

1,932,581

MICROPHONE

Louis Gilman, Chelsea, Mass., assignor to Radio
Television Industries Corporation, Boston,
Mass., a corporation of Delaware

Application April 25, 1932. Serial No. 607,242

6 Claims. (Cl. 179—122)

This invention relates to microphones and more especially to microphones for use in broadcasting.

The general object of the invention is to provide an extremely compact microphone that may 5 be attached to the person of the broadcaster, for instance, to the lapel of his coat, and which has sufficient sensitiveness and power to operate for its intended purpose, even although the voice waves are not directed toward the same as where, 10 for example, the broadcaster is addressing an audience.

Specific objects of my invention are to provide a novel means for stretching the diaphragm of the microphone so that the natural frequency 15 thereof will be higher than that of the highest audible note transmitted, in order to avoid distortion, and to provide a simple and effective means for firmly attaching to the microphone terminals the ends of the two conductors connecting 20 the device to the transmitting circuit.

An illustrative embodiment of my invention that has given good results in practice is shown in the accompanying drawing in which—

Figure 1 is a front view of a microphone embodying my improvements; 25 Fig. 2 is a rear view thereof; Fig. 3 is a central section taken on the line 3—3 of Fig. 2; Fig. 4 is a central longitudinal section on an enlarged scale of a detail of construction, and 30 Fig. 5 is an under-plan view thereof on an enlarged scale.

In the particular drawing selected for more fully disclosing my invention, 10 is a disc which 35 may be of metal, said disc having a centrally-disposed button chamber and provided with an annular rim 11. The usual button disc 13 carrying a carbon button 14 is arranged in the button chamber and is provided with a threaded stud 15 secured to the rear face thereof and co-axial therewith. In the space between the felt washer 16, button 14 and diaphragm 17 granular carbon 40 is placed. These elements of course do not form part of the present invention and are common to all microphones.

The front face of the disc 10 consists of a flat annular portion 18' between the chamber and the rim and said front face is provided with an annular groove 19 adjacent the rim 11, said 45 groove preferably having one side levelled, as shown at 20.

For stretching the diaphragm and holding the same in position, I provide an annulus 21 having a flange 22 concentric with the rim 11, the inner edge of said flange preferably being bevelled

correspondingly to the edge of the flange. In the present instance the annulus is provided with a reticulated face 23 to protect the diaphragm and permit the sound waves to impinge thereon.

After the elements making up the microphone 60 have been assembled, as hereinafter more fully set forth, the diaphragm is placed on the front face of the microphone and stretched and maintained in stretched condition by forcing the annulus 21 into the position shown in Fig. 3 where 65 it is held frictionally between the rim 11 of the button chamber and the flange 22 of the annulus. As will be obvious from Fig. 3, the diameter of the diaphragm is larger than that of the disc 10, and therefore, when the annulus is forced 70 home, the peripheral portion of said diaphragm will be disposed between the rim 11 of the disc and the flange 22 of the annulus, as indicated at 17'. A portion of said diaphragm will be forced into the annular groove 19 the bottom of which 75 is slightly inward of said flat annular portion 18' of the front face of the disc whereby a slight rim is formed on the inner face of the diaphragm, such rim assisting in maintaining the diaphragm in stretched condition. The outside diameter of 80 the flange 22 must, of course, be smaller than the inside diameter of the rim 11, and preferably the difference between said diameters is approximately twice the thickness of the diaphragm, or a little less, in order that the peripheral portion 85 of the diaphragm may be tightly clamped between said rim and flange. As will be apparent, the peripheral portion of the diaphragm is first tightly clamped between the rim and flange and thereupon further inward movement of the annulus will force the metal of the diaphragm into the annular groove 19 and give the central portion of the diaphragm the desired tension. It 90 will be noted that the annulus is secured to the disc solely by the conjoint frictional engagement 95 of its flange, the annular rim of the disc and the peripheral portion of the diaphragm interposed therebetween.

While various means will readily occur to those skilled in the art for suitably connecting the terminals of the microphone into circuit, I have found the attachment shown in Figs. 4 and 5 convenient and effective for this purpose, said attachment consisting of an insulating member 24 formed in the present instance, of two superimposed fibre strips 25, 26, held together by a pair of metallic eyelets 27, 28. The fibre strips are provided with registering apertures 29 for receiving a pair of conductors 30. The lower strip 31 is provided with a slot 31 extending between the 100

105

110

eyelet holes. Preferably the eyelets are threaded and means are provided for mechanically and electrically connecting the same to the microphone terminals. In the present instance the 5 stud 15 which, as aforesaid, is integral with the button disc 13, has threaded engagement with the eyelet 27, whereby said eyelet is mechanically and electrically connected to said disc, which constitutes one of the microphone terminals, and a screw 32 passing through the disc 10 which is in electrical connection with the other microphone terminal, viz, the diaphragm, has threaded engagement with the eyelet 28, and thereby secures the other end of the insulating member 10 to the disc. As indicated in Fig. 3, and shown more clearly on an enlarged scale in Fig. 4, the insulated conductors pass through the aperture 29 and the bare ends thereof are housed within the slot 31 and pass around the heads of the eyelet, respectively. It will be understood, of course, that the member 24 is secured in position on the rear face of the disc before the felt washer, granular carbon, diaphragm and annulus are assembled. The bare ends of the conductors are each given a turn around the heads of the eyelets and the member 24 then firmly clamped to the rear face of the disc 10 by screwing the stud 15 into the eyelet 27, turning the button disc 13 for this purpose, and then completing the attachment of said member 24 by the screw 32.

By this means the conductors are firmly clamped to their respective terminals. The washer is then placed in position, the chamber loaded with granular carbon, and the diaphragm attached and stretched in the manner above set forth. A hook 33 of any suitable design is attached in any suitable manner, as by the screws 34, to the rear face of the microphone. The conductors 30 preferably pass over said hook and are secured to the same near the free end thereof by thread 35 wrapped around said conductors and passing through the loop 36 formed in the hook near the free end thereof.

Suitable means, such as the insulating discs 37, 38, are employed for preventing electrical contact between the button disc and the disc 10.

The concrete embodiment of the present invention shown in the accompanying drawing is $1\frac{1}{4}$ " in diameter by $\frac{1}{4}$ " in thickness, weighs about two ounces, and has been found in actual practice to have the sensitivity and frequency range of much larger and heavier broadcasting microphones.

Having thus described an illustrative embodiment of my invention without, however, limiting the same thereto, what I claim and desire to secure by Letters Patent is:

1. A microphone comprising a disc having a centrally-disposed button chamber and an annular rim, a diaphragm disposed on the front face of said disc, and an annulus having a flange concentric with said rim, the peripheral portion of said diaphragm being interposed between said rim and flange and said annulus being secured to said disc solely by the conjoint frictional engagement of said flange, said annular rim and the peripheral portion of said diaphragm interposed therebetween.

2. A microphone comprising a disc having a centrally-disposed button chamber and an annu-

lar rim, a diaphragm disposed on the front face of said button chamber, and an annulus having a flange concentric with said rim, the outside diameter of said annulus being smaller than the inside diameter of said rim by approximately twice the thickness of said diaphragm, the peripheral portion of said diaphragm being interposed between said rim and flange and said annulus being secured to said disc solely by the conjoint frictional engagement of said flange, said annular rim and the peripheral portion of said diaphragm interposed therebetween.

3. A microphone comprising a disc having a centrally-disposed button chamber and an annular rim, a diaphragm disposed on the front face of said disc, said front face having an annular depression adjacent said rim, and an annulus having a flange concentric with said rim, the peripheral portion of said diaphragm being interposed between said rim and flange and a portion thereof lying in said depression, said annulus being secured to said disc solely by the conjoint frictional engagement of said flange, said annular rim and the peripheral portion of said diaphragm interposed therebetween.

4. A microphone comprising a disc having a centrally-disposed button chamber and an annular rim, the front face of said disc comprising a flat annular portion between said chamber and rim, a diaphragm disposed on the front face of said disc, and an annulus having a flange concentric with said rim, one edge of said flange being bevelled, the front face of said disc having an annular groove arranged to receive the end of said flange and one side of said groove being bevelled correspondingly to the edge of said flange, the peripheral portion of said diaphragm being disposed between said rim and flange and a portion thereof lying in said depression, said annulus being secured to said disc solely by the conjoint frictional engagement of said flange, said annular rim and the peripheral portion of said diaphragm interposed therebetween.

5. A microphone comprising a disc having a centrally-disposed button chamber, a button disc in said chamber, an insulating member provided with two spaced threaded eyelets, a stud secured to the rear face of said button disc and co-axial therewith, said stud having threaded engagement with one of said eyelets, a screw passing through said disc and mechanically and electrically connecting the second of said eyelets to said disc, said insulating member having an aperture intermediate said eyelets for receiving a pair of electrical conductors and the under side thereof being slotted to house the ends thereof.

6. A lapel microphone provided with an attaching hook on the rear face thereof, an insulating member provided with two conducting members, means for electrically and mechanically connecting said conducting members to the microphone terminals, a pair of conductors having their ends disposed between said insulating member and the rear face of said microphone and connected, respectively, to said conducting members, said conductors passing over said hook, and means securing the same to said hook near the free end thereof.

LOUIS GILMAN.
